CENTRIFUGAL EXTRACTOR

Filed April 8, 1926

UNITED STATES PATENT OFFICE

JOHN P. GAREY, OF ELMIRA HEIGHTS, AND LOUIS B. HASBROUCK, OF ELMIRA, NEW YORK, ASSIGNORS TO ECLIPSE TEXTILE DEVICES, INC., OF ELMIRA, NEW YORK, A CORPORATION OF NEW YORK

CENTRIFUGAL EXTRACTOR

Application filed April 8, 1926. Serial No. 100,580.

This invention relates to centrifugal extractors and the like, and aims to provide means for causing a liquid to move radially outward through a wound mass of yarn.

5 A particular object of the invention is to extract liquid from wound masses of yarn, such as cones of yarn. According to the invention, an individual wound mass or cone is rotated rapidly about its axis in a holder which, while permitting the centrifugal force to extract any liquid contained in the mass, prevents this force from disrupting the mass or displacing the yarn. Furthermore, the holder is so arranged that a cone 15 of yarn may quickly and easily be inserted therein or removed therefrom, thus facilitating rapid operation of the extractor.

Other objects and advantages of the invention are hereinafter explained in connection 20 with a detailed description of a specific device embodying the invention which is shown in the accompanying drawings, in which:—

Fig. 1 is a side elevation partly in axial section; and

25 Fig. 2 is an end elevation with parts broken away.

The device shown in the drawing has a frame or table 10 on which are mounted two standards 11, 11' containing bearings in 30 which a short shaft 12 is rotatably mounted. Between the standards 11, 11' means are provided for rotating the shaft 12 rapidly, for example, at 2000 R. P. M. or more. In the form illustrated, such means include a belt 35 pulley 13 fixed on the central portion of the shaft and a belt 14 running over this pulley and driven from a larger power-driven pulley located below the table 10 and not shown in the drawings. On the opposite ends of 40 the shaft 12 are mounted yarn holders 15, 15'. Each yarn holder is formed to engage the outer surface of a mass of yarn all the way about its circumference and to hold the mass with its axis coincident with that of the shaft 12. The holders are provided with perforations 16, or otherwise made foraminous, to permit the passage of liquid extracted from the masses of yarn.

Each of the holders illustrated has the 50 form of a frustum of a cone closed and mount-

ed on the shaft 12 at its smaller end and open at its larger outer end. A cone of yarn, that is, a frusto-conical mass of yarn C wound on a conical core C¹, may be inserted through the larger end of one of the holders, and, 55 when pushed inward, is firmly engaged by the holder all the way around its circumferential surface as shown at the right-hand side of Fig. 1. The roughness of the inner surfaces of the holders caused by the presence 60 of the perforations 16 assists in retaining cones in the holders.

To confine the liquid thrown off from the masses of yarn, each holder is surrounded by a casing 17. Each casing is closed at its inner end by an end wall 18 containing a central hole to permit the passage of one end of the shaft 12. The outer end wall 19 of each casing contains a large central opening 20, as large or larger than the outer end of the holder 15, or 15', to facilitate the insertion and the removal of cones of yarn. As no liquid is thrown in an axial direction, all the liquid thrown off from the cones is caught in the casings and may be removed through 70 drain pipes 21 extending from the bottoms of the casings.

The operation of the device is obvious from the foregoing description.

Among the advantages of the device it 80 should be noted that a very rapid and thorough extraction may be obtained by rotating the shaft at high velocity because of the fact that the cones of yarn are held and rotated by means engaging their outer surfaces so that the cones cannot be deformed or disrupted by the centrifugal force. The yarn may be inserted in the usual form in which it is wound so that no special winding 85 or arrangement of the yarn is necessary in preparing it for extraction. The liquid in each cone of yarn is thrown directly radially outward so that the device is applicable to the extraction of liquid from partially dyed cones as well as completely dyed cones. Furthermore, if in the dyeing or other treatment 90 of the yarn the paper core on which it is wound has become saturated with liquid and thus softened or misshapen, the core is restored to its normal shape by the centrifugal 95 100

force which urges it outward against the yarn and dries and stiffens in its normal shape.

While the device which has been described is intended primarily as an extractor, it may also be used for other purposes, for example, in carrying out a method of dyeing invented by Henry E. Van Ness and described and claimed in his application filed March 11, 1926, Serial No. 93,821. We wish it understood, therefore, that our invention is not limited to any particular use of the device described, and that it covers any modifications thereof which are within the claims that follow.

15. What is claimed is:

1. A device for extracting liquid from yarn wound in the form of yarn cones, comprising a rigid foraminous frusto-conical holder having substantially the same taper as the yarn cones, longer than the yarn cones, and open at its larger end to receive one of the yarn cones, and means secured to the holder for rapidly rotating it and a yarn cone wedged into it about the axis of the yarn cone.

20. 2. Apparatus for extracting liquid from yarn wound in a mass of predetermined form, comprising the combination with means for rotating the mass about its axis, of a foraminous confiner formed to fit tightly against the peripheral surface of the mass to prevent disruption of the mass by centrifugal force.

25. 3. In apparatus of the class described, the combination with spaced bearings and a shaft rotatably mounted thereon, of foraminous yarn holders secured to opposite ends of the shaft outside said bearings, and means engaging the shaft between said bearings for rotating it.

40. 40. In testimony whereof we have hereunto set our hands.

JOHN P. GAREY.
LOUIS B. HASBROUCK.
